UNITED STATES PATENT OFFICE.

BERYANT SIMPSON, OF WASHINGTON, DISTRICT OF COLUMBIA.

GARMENT HANGER.

Application filed August 14, 1925. Serial No. 50,315.

My present invention has reference to improvements in garment hangers, and to supports therefor.

An object is to simplify and improve the existing art by producing a garment hanger in which a garment is suspended from the device in a manner substantially similar to that in which it is arranged upon the person of the user, that is, the front and the back 10 of the garment are held in spaced relation with respect to each other so that a free circulation of air will pass through the garment, and wherein the garment will be prevented from creasing and bulging, which is especially desirable when a garment retains 15 dampness after being pressed or cleaned.

A further object is the provision of a garment hanger by the use of which separate articles of wearing apparel may be effectively supported out of direct contact with each other and in a manner to permit of the free circulation of air therebetween.

A further object is the provision of a garment hanger which may be folded or collapsed to produce a small package for shipment or storage when not required for use.

A still further object is to simplify and improve the garment hanger construction that forms the subject matter of U. S. patent 30 application, Serial No. 26,233, filed by me on April 27, 1925.

With the above recited objects in view and others which will appear as the nature of the invention is better understood, reference is 25 to be had to the drawings which accompany and which form part of this application.

In the drawings:

Figure 1 is a perspective view illustrating a two-part garment supported in accordance 40 with this invention.

Figure 2 is a perspective view of the improvement.

Figure 3 is a top plan view thereof showing one pair of the arched spreader arms 45 swung directly beneath the hanger proper, to better illustrate the arrangement of parts when the hanger is not required for use.

Figure 4 is a fragmentary perspective view of the upper portion of the standard of 50 the support.

Figure 5 is a fragmentary perspective view to illustrate a slight modification.

Figure 6 is a perspective view of a modified form of the device.

Figure 7 is a sectional view on the line 55 7-7 of Figure 6.

Figure 8 is a fragmentary side elevation of the construction disclosed in Figures 6 and 7, showing the device as when in folded or collapsed condition.

The support for my improvement is preferably in the nature of an ordinary stand which includes a flat base 1 having an upright 2 centrally arising therefrom. The upright 2 at its outer end is provided with centrally arranged transverse and longitudinal slots 3 and 4, respectively. The slots, of course, centrally intersect each other and the slot 4 is of a materially greater depth than the slot 3. As will be hereinafter apparent the hanger may be suspended from a suitable hook or the like, in which instance the vertical support is dispensed with.

In the preferred form of my invention the hanger is wholly constructed of wire. This 75 construction is best illustrated in Figures 1, 2 and 3 of the drawings. In this showing the hanger 5 has its main or body portion of a construction similar to that of the ordinary wire hanger, that is, the hanger is centrally 80 formed with a hook 6 from which are extended oppositely disposed downward angle arms 7 that terminate in angle extensions 8. In the present instance, the angle extensions have their ends bent inwardly, as at 9, and 85 from thence upwardly, as at 10. The arms 10 are wrapped or otherwise secured to the angle arms 8 at a suitable and equal distance from the sides of the hook 6.

The arms 9 are engaged by eyes 11 formed 90 on the angle ends 12 of a bar 13. This bar provides the support or hanger for the skirt portion of a two-piece lady's garment or for the trousers of a man's garment. The support 13 is swingable against the hanger 5.

The spreader arms for the garment are each, in the present instance, constructed from a single strand of suitable wire. These wire strands are arched downwardly from the center thereof and provide, which 100 for distinction I will term, front and rear arms 14 and 15, respectively. The front arms 14 are of a materially greater length than the rear arms 15. The arms 14 and 15, at the central portion of the strands constituting 105 the same are coiled, as at 16, around the vertical elements 10 of the hanger frame 5, and the lower ends of the arms 15 are bent inwardly toward the said elements 10 and are coiled therearound, as at 17. In this 110 manner it will be noted that the arms 14 and 15 are hingedly supported upon the ele-

ments 10 of the hanger frame with a result that the said arms may be swung beneath the said frame to provide a small and compact bundle when the device is not in use. 5 Both the front and rear arms 14 and 15 have their strands constituting the same rounded and extended at opposite angles to provide each of the said arms with a wavy surface and to thus widen each of the said 10 arms to provide a comparatively broad contacting surface of the arms with the inner and outer portions of the garment 18 which is arranged over the hanger. By thus widening the arms no crease will occur in the 15 garments at the portions thereof contacted by the said arms which would be true were the arms merely arched, it being understood that the said arms are constructed of wire. The outer strands of the arms 14 are 20 rounded inwardly, as at 19, and contact with one of the angle portions 20 formed with the said arms.

The eyes 17 are formed with extensions 21 that terminate in angle hooks 22, these 25 hooks being designed to snap over the elements 9 of the hanger frame 5 for holding the arms 14 and 15 at right angles with respect to the longitudinal plane of the said frame.

30 The arms 14 and 15 embody a natural resiliency and therefore the arm 14 may be readily sprung away from the arm 15. This is at times very desirable, as when the front and back of the garments are to be spaced 35 determined distances away from each other. To accomplish this I provide a rod 25 that has a hooked end 24 to engage with the arm 14. The rod is extended toward the end 23 of the arm 15, and is wound to provide an 40 eye portion 26 that receives the said end 23 therethrough. From thence the rod 25 is extended toward the eye portion 24 of the rod 25 proper. This extending portion 29 is formed with an eye 27 that receives the rod 45 25 proper therethrough. The portion 27 is bent at opposite angles and any one of these angle portions is designed to contact with the element 10. In this manner it will be noted that the front arms 14 are held at desired 50 positions with respect to the main body of the frame 5.

The frame 5, at the portion thereof provided with the hook 6, is bent to form the same with a downwardly extending U-shaped portion 30 which is designed to be received in the longer slot 4 of the supporting standard 2 when the upper and straight portions 31 of the said frame, at the opposite sides of the hook 6, and to which the arms 7 are joined, are received in the notches 3. In this manner it will be seen that the hanger is effectively supported in an upright position as disclosed by Figure 1 of the drawings.

65 In Figure 5 I have illustrated the inner

garment hanger in the nature of a wooden rod 13' which has its ends pivotally connected to links 31 which are hingedly secured to the inwardly directed lower elements or arms 9' on the ends 8' of the main 70 frame.

In Figures 5 to 8, the main frame 32 is of the ordinary wooden construction, the same being provided with a suspending hook 33 and the arched arms thereof are connected 75 together by a rod 34 that provides the hanger for the inner garment. For distinction the arched arms of the frame 32 are indicated by the numerals 35. Each of these arms has secured on its under face, at points adjacent their lower ends, an angle rod each of which constitutes a horizontal arm 9" and a vertical arm 10', assuming the hanger is in the position illustrated in the said figures. The numerals 36 indicate arched spring 80 members which at points to one side of the center thereof are coiled, as at 37, around the arms 10. The members 36 are similar to the arms 14 and 15, except that the same are in the nature of straight rods. The inner 85 and shorter arm provided by each of the arched members 36 may and preferably is rounded upon itself to provide an eye 38 and from thence extended to and formed with a second eye 39 which is arranged around the lower portion of the arm 10'. Each of the eyes has an extension directed toward the arms 9' and terminating in a hook 22' for clamping engagement with the said arms 9'. The outer ends of the arms 36 are also 90 formed with eyes, and through these eyes and through the eyes 38 there are passed securing means for arched plates 40 and 41, respectively. The plate 41 is of a less length than the plate 40. Hingedly secured to each 95 of the plates 40 there is an inwardly directed rod 25' that has one of its ends rounded to provide an eye 28' that is arranged around the extension 23' on the inner end of the arched arm 36. The eye 28' has its end 100 formed with an extension 29'. This extension has an eye end 27' which is arranged to receive therethrough the rod 25'. The extension 29' is stepped to provide straight shoulders and angle portions between said shoulders. Any one of the shoulders is 105 designed to contact with the arm 9' and thereby hold the arched plates 40 at desired angles with respect to the main frame 32. This 110 construction is employed in a similar manner as that previously described and when the device is not desired for use the arched rod plate carrying arms may be swung directly below and in a plane with the main hanger frame 32 as disclosed by Figure 8 of the drawings. In Figure 7 the manner of 115 adjusting or swinging the arm or plate 40 toward the main frame is illustrated by the dotted lines.

120 The simplicity of my construction and the 130

advantages thereof will, it is believed be perfectly apparent to those skilled in the art to which such invention relates, when the foregoing description is read in connection 5 with the accompanying drawings.

Having described the invention, I claim:—

1. The combination, a suit hanger including an arched frame, and arched members depending from and pivotally supported below the sides of the frame, and swingable 10 laterally of the frame.

2. The combination, a suit hanger including an arched frame, and arched members depending from and pivotally supported below the sides of the frame, and swingable laterally of the frame and means for latching the arched members in such position.

3. A garment hanger including a frame, 20 having an inner garment support thereon, arched members depending from and pivotally supported on the frame adjacent to the ends thereof, means for latching the arms when arranged rightangularly with respect 25 to the longitudinal plane of the frame, and means for adjusting the arms toward or away from the frame.

4. A garment hanger comprising a frame having at its lower ends depending arms 30 which merge into rightangular arms that are connected to the top of the frame, an inner garment hanger pivotally supported from the first mentioned arms, arched members pivoted to one side of their center, to

the upper portions of the last mentioned 35 arms, the shorter sides of the arched members having extensions which are hingedly connected to the lower portions of the last mentioned arms and which are formed with hooks to engage the first mentioned arms to 40 hold the arched members rightangular with respect to the frame.

5. A garment hanger comprising a frame having at its lower ends depending arms which merge into rightangular arms that 45 are connected to the top of the frame, an inner garment hanger pivotally supported from the first mentioned arms, arched members pivoted to one side of their center, to the upper portions of the last mentioned 50 arms, the shorter sides of the arched members having extensions which are hingedly connected to the lower portions of the last mentioned arms and which are formed with hooks to engage the first mentioned arms to 55 hold the arched members rightangular with respect to the frame, a rod connected to the outer portions of the arched members and slidable upon the inturned portions at the second ends of the said arched members, 60 and said rods having stepped extensions for contacting engagement with the first mentioned arms of the frame for sustaining the outer portions of the arched members at desired positions relative to the frame. 65

In testimony whereof I affix my signature.

BRYANT SIMPSON.
